CLAIM

The ornamental design for a hanger assembly for a birdfeeder, as shown and described.

DESCRIPTION

FIG. 1 is an isometric view of a hanger assembly for a birdfeeder showing our new design with other portions of a birdfeeder.

FIG. 2 is an isometric view of the hanger assembly for a birdfeeder.

FIG. 3 is a bottom perspective view thereof.

FIG. 4 is a side view thereof.

FIG. 5 is a front view thereof.

FIG. 6 is a top view thereof; and,

FIG. 7 is a bottom view thereof.

The broken lines in the Figures show environment forming no part of the claimed design or show portions of the hanger assembly for a birdfeeder that form no part of the claimed design. The shade lines in the Figures show contour and do not claim surface ornamentation or treatment.
